UNITED STATES PATENT OFFICE

131,694

DESIGN FOR A COIN BANK

Clarence R. Sutherland, Dayton, Ohio

Application July 16, 1941, Serial No. 102,183

Term of patent 7 years

To all whom it may concern:

Be it known that I, Clarence R. Sutherland, a citizen of the United States, residing at Dayton, Montgomery County, Ohio, have invented a new, original, and ornamental Design for a Coin Bank, of which the following is a specification, reference being had to the accompanying drawing, forming a part thereof, in which—

Fig. 1 is a side view of a coin bank embodying my new design, and

Fig. 2 is a perspective view thereof.

I claim:

The ornamental design for a coin bank, substantially as shown.

CLARENCE R. SUTHERLAND.
